Des. 208,258
Patented Aug. 8, 1967

208,258

GAME BOARD

Robert W. Bingham, 3642 Imperial Gardens
St. Louis County, Mo.

Filed Apr. 29, 1966, Ser. No. 2,062

Term of patent 14 years

(Cl. D34—5)

The dominant features of the design reside in the full line portions shown.

I claim:

The ornamental design for a game board, substantially as shown and described.
